Specification for Design.

Patented Mar. 7, 1916.

Application filed August 9, 1915. Serial No. 44,657. Term of patent 14 years.

To all whom it may concern:

Be it known that I, ALVIN V. ROWE, a citizen of the United States, residing at Galesburg, county of Knox, Illinois, have invented a new, original, and ornamental Design for Rubbing Devices for Animals, of which the following is a specification, reference being had to the accompanying drawing, forming a part hereof, and in which—

Figure 1 is a side elevation of a rubbing device for animals, showing my new and ornamental design; Fig. 2 is a top plan view of the same; Fig. 3 is a top plan view of the base portion.

I claim:

The ornamental design for a rubbing device for animals, as shown.

ALVIN V. ROWE.
